(57) CLAIM

The ornamental design for a dish towel, as shown and described in the Figures.

DESCRIPTION

FIG. 1 is an isometric view of the dish towel;

FIG. 2 is a top side view of the dish towel;

FIG. 3 is a rear side view of the dish towel;

FIG. 4 is a side view of the dish towel;

FIG. 5 is a side view that is opposite the side view of FIG. 4 of the dish towel;

FIG. 6 is a top side view of the dish towel; and,

FIG. 7 is a bottom side view of the dish towel.

The broken lines in the drawings form no part of the claimed design.

1 Claim, 5 Drawing Sheets
